UNITED STATES PATENT OFFICE.

RICHARD L. B. RATHBONE, OF LONDON, AND CAVENDISH MORTON, OF THORNTON HEATH, ENGLAND.

HAND TOOL FOR GRIPPING, BENDING, OR CUTTING OPERATIONS.

Application filed September 7, 1921. Serial No. 499,038.

To all whom it may concern:

Be it known that we, RICHARD LLEWELYN BENSON RATHBONE, a subject of the King of Great Britain and Ireland, and residing at 5 3 Ravenscourt Square, Hammersmith, London, W., England, and CAVENDISH MORTON, a subject of the King of Great Britain and Ireland, and residing at 33 Torridge Road, Thornton Heath, in the county of Surrey, 10 England, have invented a certain new and useful Improved Hand Tool for Gripping, Bending, or Cutting Operations, of which the following is a specification.

The present invention relates to hand-tools, such as pliers, tweezers, forceps or the like which are commonly employed for gripping, bending or cutting metal or other materials.

In the specification of British application 20 No. 9739 of 1921, we have described a tool in which the jaws are provided with interchangeable nose-pieces.

The present invention is concerned with tools of this general type, and in particular 25 with an improved construction whereby jaws of various shapes may be very readily substituted the one for the other.

According to the present invention we provide a tool-operator comprising a metal 30 strip or the like bent to U-shape or similar form, the arms so produced being capable of being pressed together either by hand or by means of a suitable lever, and adapted to receive in the bend between them the shanks 35 of any two of a set of interchangeable jaws having various shapes.

One means of carrying out our invention is illustrated in the accompanying drawings, in which

40 Figure 1 is a side view of the tool-operator, the position occupied by the detachable jaws being indicated in dotted lines.

Figure 2 is a side view of one form of 45 detachable jaws suitable for fitting in the tool-operator shown in Figure 1.

Figure 3 illustrates a form of cutter also suitable for insertion in the tool-operator depicted in Figure 1.

Figures 4 and 5 are sectional views on 50 the line A—B of the cutter shown in Figure 3, looking in opposite directions.

In the form of the invention illustrated in Figure 1, the tool-operator comprises a strip of metal 1 bent to U-shape, the arms

of the U being confined by a guide 2 within which they may be moved toward and away from one another by means of a suitably shaped lever 3 attached to the guide. The jaws 4 of the tool are formed on opposite ends of a bar 5, also bent to a U-shape 60 of such a size that it will fit within the tool-operator 1, while allowing the jaws to project beyond the arms of the operator.

Obviously the jaws 4 may be made of any desired shape, and it is not necessary that 65 co-operating jaws should be of the same shape. For instance, one jaw might be made of round and the other of flat rectangular section. In the cutter illustrated in Figures 3 to 5, the jaws 6 and 7 are preferably 70 detachable from a short U-shaped bend 8, the whole being of such dimensions that it can be inserted in the operator 1. The jaw 6 is preferably made straight, and has engraved on it a scale 9, by means of which 75 the length of wire, strip or the like which is being cut off may be indicated. A stop 10, which may be secured at any point along the jaw 6 by such means as a screw 11 enables a number of equal lengths to be cut 80 off with great facility.

In order to prevent tilting of the wire or the like as the cutting edges are brought together, a flat spring 12 is preferably attached to the curved jaw 7, so that it bears upon the 85 wire or the like which is being cut, just before the jaws meet, and holds it firmly against the jaw 6.

If it be desired that the tool shall operate as a cutter rather than as a shearing tool, 90 we bend the lower jaw upwards sufficiently to enable a cutting edge to be formed on the bent-up portion, the upper jaw being also formed with a cutting edge arranged to meet that of the lower jaw. In such a case it 95 may be found unnecessary to fit a spring or block, since, provided the edges meet accurately, the tendency to tilting of the wire or the like does not exist. If, however, in order to steady the wire or to compensate for any 100 possible inaccuracy in the meeting of the cutting edges, we find it desirable to fit a spring or block, it may be necessary that this provision be made on both jaws.

In order to allow for relative adjustment 105 and for easy sharpening or grinding of the shearing or cutting edges, we preferably connect the rear ends of the jaws to the U-

shaped bend 8 by means of screws, the clearing holes for the screws being formed as slots to enable one jaw to be moved slightly over the other.

5 It will be seen that any number of U-shaped bars having jaws of any desired form may be provided to fit into a single tool-operator, and particularly if the strip of which the operator is made be of channel section, it is not necessary to provide any means for retaining the U-shaped shank of the jaws within the operator, thus enabling a very rapid change to be made from one pair of jaws to those of another shape.

15 There may be cases in which it is desirable to use two jaws of dissimilar form, and for this purpose we may form the jaws entirely separately, that is to say, without a common U-shaped shank, each being provided with its own shank which will fit into or on to and be held by the tool-operator. In order satisfactorily to hold a shank of this type which will in general merely consist of a straight bar, we may find it desirable to make the arms of the tool-operator of a box-like formation, and further it may be desirable to provide screws or other fixing means for retaining the shanks of the jaws in position.

25 30 It will be seen that the lever described whereby the jaws are brought together is not an essential of the invention, and in some cases it may be desirable to omit this lever, the tool-operator in that case being held in the hand and its arms being brought together by pressure between the thumb and fingers.

Having now described our invention what we claim as new and desire to secure by Letters Patent is:—

45 1. In combination, a tool-operator having a pair of associated operator members movable towards and from one another and a tool having a pair of associated legs similarly movable, said tool being insertable in said tool-operator with the legs of said tool in operative relation to said operator members, as set forth.

50 55 2. In combination, a tool-operator having a pair of operator members movably associated at one end and approximated at the other; and a tool having a pair of legs mutually operative at the one end and movably associated at the other, said tool legs being disposed between said operator members in

operative pressure-transmitting relation thereto, as set forth.

3. In combination, a tool-operator having relatively movable operator members, said tool-operator forming a self-contained operative unit and a two-legged tool also forming a self-contained operative unit, said tool being insertable between said operator members and in operative relation thereto, as set forth. 60 65

4. In combination, a U-shaped tool-operator having relatively movable operator members and a U-shaped tool insertable in said tool-operator in operative relation to said movable members, as set forth. 70

5. In combination, a tool-operator having relatively movable operator members and a two-legged tool nestable within said members and in operative relation thereto, as set forth. 75

6. In combination, a tool-operator having relatively movable operator members, a two-legged tool insertable between said operator members in pressure-transmitting relation thereto; and mechanical means associated with said operator members to cause said operator members to approach, as set forth. 80

7. In combination, a U-shaped tool-operator having relatively movable operator members; a two-legged tool insertable in said tool-operator together with mechanical means mounted on said tool-operator for causing said operator members to approach, as set forth. 85

8. In combination, a tool-operator having relatively movable operator members and a plurality of two-legged tools interchangeably nestable within said operator and in operative relation thereto, as set forth. 90

9. In combination, a tool-operator having relatively movable operator members and a two-legged tool insertable in said tool-operator, the ends of the legs of said tool projecting beyond said operator members, as set forth. 95

10. In combination, a tool-operator having relatively movable operator members and a U-shaped tool having at least one detachable leg, said tool being insertable in said operator in operative relation thereto, as set forth. 105

In testimony whereof we have signed our names to this specification.

R. L. B. RATHBONE.
CAVENDISH MORTON.
